Patented Nov. 5, 1912.

UNITED STATES PATENT OFFICE.

AUGUST JOHNSON, OF GULLIVER, MICHIGAN.

KEEPER FOR DOOR AND GATE LATCHES.

1,043,236.

Specification of Letters Patent.

Patented Nov. 5, 1912.

Application filed July 17, 1911. Serial No. 638,918.

To all whom it may concern:

Be it known that I, AUGUST JOHNSON, a citizen of the United States, residing at Gulliver, in the county of Schoolcraft and 5 State of Michigan, have invented certain new and useful Improvements in Keepers for Door and Gate Latches; and I do declare the following to be a full, clear, and exact description of the invention, such as will 10 enable others skilled in the art to which it appertains to make and use the same.

This invention relates to latches, and more especially to the keepers thereof; and the object of the same is to greatly simplify 15 and yet improve and strengthen the construction of the keeper in such a way that it may be used with a latch on a door which slides or swings.

With this object in view, the invention 20 consists of certain novel features of construction, and the combination and arrangement of parts as will be more fully described and claimed.

Figure 1 is a side view of one side of a 25 portion of a door and door frame or casing showing the application of my improved latch; Fig. 2 is a similar view of the opposite side of the door; Fig. 3 is a vertical sectional view on the line 3—3 of Fig. 1; 30 Fig. 4 is a horizontal sectional view on the line 4—4 of Fig. 1; Fig. 5 is a detail perspective view of the latch plate; Fig. 6 is a similar view of the keeper.

In the embodiment of the invention I provide 35 a latch plate 1 which may be of any suitable size according to the size of the door or gate to which the same is to be applied. The latch plate 1 has formed in its inner end a square aperture with which is engaged the squared shank 2 of an operating handle 3 which projects rearwardly from and at right angles to the latch plate as shown. The shank 2 extends through an opening in the door and projects a suitable 40 distance beyond the opposite side of the door and through a washer 4 arranged adjacent to this side of the door as shown. With the square projecting end of the shank is engaged a second operating handle 5 said 45 handle being secured to the shank by means of a nut 6 screwed onto the end of the shank, said end being reduced and threaded as shown to receive the nut.

The outer or free end of the latch plate 55 is beveled or inclined from the lower edge toward the upper edge of the plate as at 19

and said beveled end terminates in a reduced extension which is preferably bent upwardly, thence rearwardly and downwardly into a loop 20 standing upon the 60 upper edge of the plate as shown. In the lower edge of the latch plate adjacent to the beveled end thereof is formed a locking notch 7 the purpose of which will be herein-after described. In the center of the plate 65 1 at the rear of and spaced a suitable distance from the notch 7 is formed a threaded aperture 8 into which is adapted to be screwed the threaded stem of an eye bolt or locking member 9, said eye bolt or lock- 70 member being adapted to be screwed into the aperture 8 from either side of the latch plate thus permitting the latch to be used on either side of doors or on doors opening at the left or right hand side. Secured to the door adjacent to the edge of the 75 same is a guide or guard loop 10 through which the free end of the latch plate extends and is adapted to operate, said guide loop holding the free end of the latch plate 80 in place and supporting the same in position when the door is open.

Secured to the door frame or casing in position to be engaged by the latch plate is a keeper 11, said keeper being preferably constructed from a wire rod bent to form an outstanding or horizontal arm 15, an upwardly and inwardly inclined portion 16 leading from the outer end of said arm, a rounded loop 17 into which the upper end 90 of the incline 16 merges, and a screw 14 at the inner end of the loop standing parallel with the arm 15 but above it, the screw making an angle with the inner side of the loop so as to produce a depression or offset 95 which is intended to receive the beveled end of the latch plate and to be engaged by the locking notch 7 in the lower edge of the same. The lower end 18 of the rod forming the keeper extends straight downward from the inner end of the arm 15 and is pierced with an eye 19 through which is adapted to be passed a bolt 13 by means of which the lower portion of the keeper is rigidly secured to the door frame. In putting this 100 improved keeper into place, the point of its screw 14 is inserted in the door frame first and the whole keeper revolved around it to sink this screw in the wood until the inner side of the lower end 18 comes in contact 105 with the wood and stands below the screw 14 as seen in Fig. 3, at which time the re-

cess 12 will be interposed between the inner arm of the loop 17 and the outer face of the wood so as to conveniently engage the free end of the latch; and finally the bolt 13 is applied to hold the keeper rigidly in position.

The loop 17 stands at a point in line with the eye bolt 9 to be engaged by a padlock whereby the latch plate may be locked in a closed or operative position.

By constructing and arranging my improved latch as herein shown and described the same may be readily applied to a swinging or sliding door and will automatically 15 catch or engage the keeper when the door is swung or slid to a closed position. When applied to a hinged or swinging door and the latter is swung to a closed position the lower edge of the latch plate will engage 20 the inclined outer edge 16 of the keeper which engagement will lift the latch plate and permit the same to pass over the loop 17 and to drop into the locking recess 12. When the latch is applied to a sliding door 25 and the latter closed the beveled end 21 of the latch plate will come into engagement with the lower end of the recess 12 thereby raising the free end of the latch plate and thus permit the notched lower edge thereof 30 to drop into engagement with the lower portion of the recess 12 in the keeper thus automatically locking the latch plate in engagement with the keeper. In either use of this device, the upstanding loop 17 of the keeper 35 serves the double purpose of assisting in retaining the tip of the latch plate and presenting an opening coöperating with that in the eye-bolt 9 to receive a padlock. The rear arm of the loop 17 positively resists the 40 opening of a swinging door, and the lower portion of the recess 12 (which is the outer extremity of the screw 14) positively resists the opening of a sliding door—the latch plate engaging in the angle between these 45 two parts whether the door swings or slides.

In releasing the latch for opening either a sliding or swinging door it is simply necessary to bear down on the handle at either side of the door whereupon the free end of

the latch will be lifted out of engagement 50 with the recess or depression in the keeper thus permitting the door to be swung or slid back to an open position. By arranging the handles of the latch in the manner described, said handles serve not only as a means for 55 operating the latch but also as handles for opening and closing the door, thus obviating the necessity of any other knobs or handles.

From the foregoing description taken in 60 connection with the accompanying drawings, the construction and operation of the invention will be readily understood without requiring a more extended explanation.

Various changes in the form, proportion 65 and the minor details of construction may be resorted to without departing from the principle or sacrificing any of the advantages of the invention as claimed.

Having thus described my invention, what 70 I claim is:

As a new article of manufacture, the herein described latch keeper made from a single piece of wire having an upright lower end adapted to lie against the face of the member to which the keeper is applied and pierced with an eye for a fastening screw, the wire extending from the upper extremity of said lower end outward in a horizontal arm, thence obliquely upward and inward toward said member and merging into a rounded loop, thence vertically downward toward said arm but on a line further remote from said member than is the lower end, thence forming a right angle to produce a recess for receiving the latch, and terminating in a straight screw standing parallel with but above said horizontal arm and projecting beyond said upright lower end so that the screw may embed the member, substantially as described.

In testimony whereof I have hereunto set my hand in presence of two subscribing witnesses.

AUGUST JOHNSON.
